(57) CLAIM

The ornamental design for a display box, as shown and described.

DESCRIPTION

FIG. 1 is front perspective view from above and to one side of a display box embodying our new design;

FIG. 2 is a front, elevational view thereof;

FIG. 3 is a left side elevational view thereof, the right side being the mirror image thereof;

FIG. 4 is a top view thereof;

FIG. 5 is a rear view thereof;

FIG. 6 is a bottom view thereof;

FIG. 7 is a front perspective view from above and to one side of a second embodiment of a display box identical to the first embodiment in top view, bottom view, rear view, left view and right view; and,

FIG. 8 is a front, elevational view of the second embodiment.

The broken line representations of openings on the front panels of the embodiments of FIGS. 1, 2, 4, 7 and 8 and the broken line representations of openings in the top panels of the embodiments of FIGS. 1, 4, and 7 are shown for the purposes of illustration only and form no part of the claimed design.
